UNITED STATES PATENT OFFICE.

CLAYTON ORVILLE WHITE, OF DE BEQUE, COLORADO.

METHOD AND APPARATUS FOR DISTILLING OIL SHALE.

Application filed September 26, 1927. Serial No. 221,973.

This invention relates to improvements in a method and apparatus for distilling oil shale.

Owing to the great demand for gasoline and other hydrocarbon products and oils and in anticipation of a probable depletion of the great stores of underground oil, experiments are constantly being carried on for the purpose of discovering the most practical way of treating oil shale for the purpose of obtaining oil and gasoline. These experiments have shown that this problem many difficulties that must be overcome before the production of oil from shale can be successfully carried out on a commercial basis.

Since the treatment of oil shale requires the application to the shale of high temperatures, it is obvious that the retorts in which the shale is heated must not have mechanisms having a number of relatively movable parts as it is impossible to properly lubricate bearings that are located inside of such retorts.

In my copending applications, Serial Numbers 152,889 and 203,640, filed respectively on December 6, 1926 and July 5, 1927, I have shown shale education retorts in which the shale moves through the heated zone by the action of gravity alone and which have wide flat bottoms that permit the ground shale to spread out into a thin flat layer in which the particles will roll and come into close contact with the heated metal surface of the bottom. In application Serial Number 152,889 my retort has been shown as of a length of about one hundred feet or over for the reason that the great speed at which the ground shale will travel will carry it through the heated zone too quickly unless the path is made quite long. In my application Serial Number 203,640, I have shown a retort that embodies some of the ideas of the retort shown and described in my other application, but which is formed from a plurality of angularly related sections that form a zig-zag path and in which the velocity of the shale is reduced to practically zero at the intersection of each section.

It is the object of this invention to produce a retort that shall combine the desirable features of the two retorts which have been shown and described in my prior applications and which, briefly described, con-

sists of an elongated retort having a wide flat bottom over which the ground shale will flow under the influence of gravity. At spaced intervals the retort is provided with means for reducing the velocity of the shale practically to zero so that the speed or velocity can be kept as low as desired, thereby increasing the time that it will take for the shale to pass through a retort of a given length.

My invention can be best described and will be most readily understood when reference is had to the accompanying drawings in which the invention has been illustrated and in which:

Fig. 1 is a longitudinal vertical section through a retort constructed in accordance with the preferred form of my invention;

Fig. 2 is a section taken on line 2—2, Fig. 1;

Fig. 3 is a longitudinal section of a portion of my improved retort shown in perspective to a somewhat enlarged scale;

Fig. 4 is a section through one of the velocity-retarding devices;

Fig. 5 is a vertical section through a retort embodying another form of my invention;

Fig. 6 is a longitudinal section through a section of the retort illustrated in Fig. 5; and

Fig. 7 is a section taken on line 7—7, Fig. 6.

In Fig. 1 of the drawing I have shown what I consider to be the preferred embodiment of my invention. In this embodiment the retort is built on the side of a hill and has a downward inclination of substantially forty-five degrees. Reference numeral 1 designates the inclined surface and 2 designates the masonry or brickwork which constitutes the furnace chamber of my retort. This furnace chamber is supported on concrete foundations 3, which are set into the ground in such a way that the parts will be firmly anchored so that there will be no danger of having the structure slide downwardly. The upper end of the furnace chamber terminates in a smokestack or chimney 4 which may be of any height desired. At the lower end of the furnace I have provided a recess 5 within which is located one or more gas burners 6 that serve to produce the heat necessary for the treatment of the shale. It is of

course evident that as many burners may be provided as are found to be necessary for the purpose of producing the necessary amount of heat.

5 In order to employ my apparatus it is necessary to reduce the ore to a powder or to small particles and this is accomplished by means of a grinder or crusher which has been indicated by reference numeral 7. This
10 crusher is connected by means of a chute 8 with a storage bin 9 which is provided with an inclined bottom 10. A hollow tube or conduit 11 communicates with the interior of the bin 9 and extends to the control valve
15 12. The delivery side of the control valve opens into the upper end of the retort 13. The construction of the retort constitutes the gist of this invention and has been illustrated quite clearly in Figs. 3 and 4, from
20 which it will be seen that the retort consists of a plurality of sections which have been indicated by "A". These sections each consists of a conduit formed from steel plates and which has a flat bottom 14 and also may
25 have a flat top 15. The bottom and top plates are connected by means of narrow sides 16. The width and thickness of this conduit can be varied to suit the different conditions, but as an example it will be considered that plates 14 and 15 are twenty-four inches wide and that the sides 16 are three inches wide, the conduit will therefore have the shape of a rectangle like that shown in Fig. 2. The bottom plate of each section
30 35 terminates in a short piece 17 that is bent at right angles to the plane of the bottom and whose lower end is integral with or welded to the upper end of the bottom plate of the next lower section. Part 17 has a width substantially equal to the thickness of the conduit so that the top plates 15 of the next lower section will lie in the plane of the bottom 14 of the section directly above. The top plate of each section extends downwardly some distance below the part 17 where it terminates in a downwardly extending wall 18 that is connected with the upper end of the top plate 15 along line 19. This connection may be formed by welding or in
40 45 any other suitable way so as to make a strong gastight joint. The stop plate 20 is secured to the under side of plate 15 a short distance below the wall 17 and extends to within a short distance of the bottom plate 14 of the next lower section so as to leave a narrow slot or opening 21 through which the ground shale may pass in the manner indicated in Fig. 4. A gas takeoff conduit such as that indicated by reference numeral 22 projects
50 55 60 to the side of the retort directly below the stop plates 20. The retort can be made as long as desired and the length of each section can be adapted to fit the requirements of the practical installation.

65 In Fig. 1 I have shown my retort as sup-

ported on a plurality of spaced channel irons 23 that are located underneath the bottom of each section directly above the wall 17. The lower end of the lowermost section terminates in a valve 24 which has 70 a hollow cylindrical member that can be rotated so as to remove the spent shale without opening the lower end of the retort to the admission of air. This valve may be operated periodically or it may be operated 75 continuously by means of a motor. The gas takeoffs 22 extend to a condenser 27 that is located adjacent the furnace chamber and serves to condense the gas that has been liberated from the shale. The operation of 80 this retort is as follows: The oil shale is first ground to a powder or so that the particles are quite small and will flow freely. Gas is introduced through suitable pipes and mixed with air and this mixture is 85 burned in the burner 6, thereby producing an intense heat which travels upwardly through the furnace chamber and heats the bottom of the retort sections to a very high temperature. When the valve 12 is open 90 powdered shale will flow downwardly over the upper surface of the bottom plates 14, and, owing to the fact that these plates are flat the shale will spread into a thin layer 95 which covers the entire width of the bottom as the shale particles are acted upon by the force of gravity, they will constantly increase their velocity due to the acceleration thus produced. If the retort had one 100 straight bottom surface, the speed due to the acceleration of gravity would soon become very great with the result that the shale would pass too quickly through the heated zone of the retort. This is objectionable for 105 the reason that it requires the retort to be made very long and therefore increases the expense of its construction. In the retort which I have shown in Figs. 1 to 4 and which has just been described, the powdered shale which has been designated by reference numeral 28 in Fig. 4 flows downwardly 110 over the bottom plates 14 in a thin layer which permits the particles to roll and to move about in such a way that every particle comes into contact with the metal surface and becomes thoroughly heated. When this shale powder reaches the angle between parts 17 and 14, it will have attained 115 a considerable velocity and will flow across the space between the wall 17 and the stop plate 20 and strike the latter so as to come practically to a stop. The powder will then flow along the side of the stop plates 20 and on to the bottom 14 of the section directly beneath and will continue its flow 120 until it reaches the next stop plates at the juncture of the other two sections. It is apparent that by this means the velocity of 125 this shale powder is decreased and practically reduced to zero at the beginning of 130

each section and therefore the powder will only attain such a velocity as can be reached while it flows along the bottom plate of one section. By making the sections very short, it is apparent that the velocity can be kept down to a very modest value, while if a greater velocity is desired, the length of the sections can be increased.

From the above it will be apparent that 10 a retort constructed in the manner described may have a total length as great as may be found desirable and at the same time the velocity of the powder can be maintained very low and in this manner it is possible 15 to obtain a more thorough and complete heating of the powder particles than with a retort whose bottom surface lies in one plane from one end of the retort to the other. This construction permits the retort 20 to be made much shorter than would otherwise be possible and still obtain the most complete elimination of the hydrocarbons from the shale.

In Figs. 5, 6 and 7 I have illustrated another embodiment of my invention. The retort shown in these figures is substantially the same as that described and shown in my copending application, Serial No. 203,640 and differs from that illustrated in Figs. 1 30 to 4 mainly in this, that it is designed for use in a device having a vertical zigzag furnace chamber, whereas, the one shown in the other figures is intended to be used with an incline furnace chamber like that shown 35 in Fig. 1.

In Fig. 5 reference numeral 29 represents the brick or masonry work of the furnace. This furnace has a zigzag chamber consisting of sections "C" and "D" which 40 terminate in a smokestack 30. The retort is formed of a plurality of sections 31 and 32 which are all constructed in the same manner and which have flat bottoms 33 and flat tops 34 connected by narrow side members 35. In the drawing the different sections make an angle of ninety degrees with each other and the tops 34 of the different sections connect with the upper ends of the bottoms 33 of the sections directly beneath. 50 The bottoms 33 of each section project beyond the plane of the sides 34 of the section below and terminate a short distance from the upper surface of the bottoms 33 so as to leave a narrow opening 36 through which 55 communication is had between the interior of adjacent sections. Gas takeoffs 37 are secured to the tops 34 directly below the bottoms of the sections, and these takeoffs extend to and communicate with the interior 60 of the condenser 38. Powdered shale is placed in the hopper 39 and admitted to the upper section of the retort by means of a valve 40. This shale spreads over the 65 upper surface of the bottoms 33 and flows downwardly under the influence of gravity.

As the powdered shale reaches the end of the bottoms 33, it strikes the upper end of the bottom 33 of the section directly beneath and has its velocity reduced practically to zero. As it passes through the opening 36 70 its velocity is gradually increased by the action of gravity and is reduced again when it strikes the bottom of the next succeeding section. It will be seen from this description that regardless of the total length of the retort, the velocity that can be attained by the powdered shale is limited to that which is reached during the flow over the surface of any one section, as the velocity is reduced practically to zero when it strikes the bottom of the section below. In this manner it is therefore possible to keep the shale in the heated zone for a much longer time than if this reduction of velocity at 75 spaced intervals did not take place.

In the construction here shown and described the shale passes in a practically solid stream across the opening between wall 17 and the stop plates 20 and does not have any showering effect at this point. As it 80 leaves the edge of plates 20, it is deposited on the bottom 14 in a layer whose thickness is substantially equal to the width of the gap 21 so that in effect there is a steady flow of shale across and through these two 85 gaps. In the embodiment shown in Figs. 6, the shale as it leaves the bottom plate 33 of the section above merely makes a right angle turn and flows downwardly along the bottom of the next section and therefore 90 there is no showering of the shale through the heated zone, which showering I consider to be objectionable for the reason that it causes powdered shale to become mixed with the gas and this powder will flow 95 through the pipes 37 into the condenser where it will be mixed with the condensate. By means of my construction the production of a loose powder is prevented and thereby a clear product obtained.

I also want to call attention to the fact that with my construction of retort the shale is constantly moving and therefore there is no opportunity for it to cake and to clog the retort.

Another advantage to which I have previously called attention is that the shale is moved through the retort without the use of any mechanism and therefore there is no danger of breakage and no objectionable wear such as would be the case if some mechanical means were provided for moving the shale.

By spreading the shale thinly over flat surfaces and permitting it to move downwardly by the action of gravity, all the shale is agitated so that all the particles will have an opportunity to come into contact with the heated bottom surface and to be raised to the necessary temperature. I 125 130

consider that the agitation of the shale by its downward flow is of great importance as the several particles thereby come into intimate contact and have their temperatures raised to the degree necessary for complete elimination of the hydrocarbons.

Where the shale particles do not come into contact with the heated surface, the heat does not seem to penetrate them as readily as it does when actual contact is made. The reason for this is perhaps that heat is more readily conducted by conduction and therefore the flow of heat is much faster than when the shale is in contact with the heated metal than if the particles were merely suspended in an atmosphere raised to the same temperature.

Having described my invention what I claim as new is:

20 1. In an oil shale retort the combination of a plurality of interconnected hollow sections, each having a flat bottom, the bottom surfaces of said sections lying in different planes and being inclined at an angle greater than the angle of repose for powdered oil shale whereby oil shale will flow by the action of gravity alone, and means located at the juncture of each of the sections for abruptly changing the direction of flow of 25 the shale whereby the velocity is reduced.

2. An oil shale retort comprising a plurality of interconnected enclosed metal sections forming a conduit, each section having a flat bottom, the bottoms of the several 30 sections lying each in a separate plane, the plane of each bottom section being inclined to the horizontal at an angle that is slightly greater than the angle of repose for powdered shale whereby the latter will flow by the influence of gravity alone from the top to the bottom of the retort, means located at the junction of adjacent sections for abruptly changing the direction of flow and thereby reducing the velocity of the powdered shale as it passes from a higher to a lower section, and gas takeoffs for removing the volatile products.

3. An oil shale retort comprising a gastight metal conduit composed of a plurality of 35 nonaligned sections, each section having a flat wide bottom inclined to the horizon at such an angle that powdered shale will flow over the upper surface thereof by the action of gravity alone, a stop plate extending downwardly across the plane of the bottom of each section directly beneath the lower end of the bottom whereby the powdered shale will strike the stop plate and have its velocity greatly reduced as it passes from 40 an upper to a lower section, a gas takeoff conduit located below each stop plate, and means for heating the retort.

4. In an oil shale retort the combination of a plurality of interconnected, nonaligned 45 tubular sections having flat bottoms that

lie in spaced, substantially parallel planes, said retort being formed from metal, the transverse section of the retort forming a closed area, the bottoms of the sections being inclined to the horizontal at an angle 50 greater than the angle of repose for powdered shale whereby the latter will flow by the action of gravity alone, the top of each section extending downwardly a greater distance than the bottom, a baffle plate secured to the top of each section and extending transversely of the plane of the bottom, but spaced from the lower end of the latter, the lower edge of the baffle terminating a short distance from the bottom of the next 55 lower section and a gas takeoff adjacent each baffle.

5. In an oil shale retort the combination of a chamber closed at the top and inclined to cause the shale to travel downwardly 60 therethrough by gravity alone, the bottom of the chamber being stepped downwardly at intervals, and baffles respectively located below and spaced from but adjacent to the step offsets of the bottom of the chamber, 65 the said baffles being in the path of the shale and retarding the normal speed due to gravity acceleration, whereby the period of travel of the shale through the chamber is increased and the length of the retort required 70 in order to properly heat the shale, correspondingly diminished.

6. An oil shale retort comprising a chamber closed at the top and inclined to cause the shale to travel downwardly therethrough 75 by gravity alone, the bottom of the chamber being stepped downwardly abruptly at intervals, and baffles respectively located below and spaced from but adjacent to the step offsets of the bottom of the chamber, 80 the said baffles being in the path of the shale and retarding the normal speed due to gravity acceleration, whereby the period of travel of the shale through the chamber is increased and the length of the retort required 85 in order to properly heat the shale, correspondingly diminished, means for heating the chamber and a gas takeoff communicating with the chamber adjacent to each baffle.

7. The method of distilling oil shale 90 which consists in reducing the shale to small particles and passing the said reduced product in a thin layer of substantially uniform thickness through a heated chamber in a direction inclined to cause the shale to travel 95 by gravity alone, the stream of shale being stepped downwardly at intervals and baffled a short distance below each of said step movements, to check the speed due to gravity acceleration, but without stopping its 100 travel, and removing the volatile products.

8. The method of distilling oil shale which consists in reducing the shale to a finely divided condition, passing this product in a thin layer of substantially uniform 105

depth, through a heated chamber and in a direction inclined to the horizontal, to cause the shale to travel by gravity alone, the stream of shale being stepped downwardly 10
5 at intervals during its passage through said chamber and baffled adjacent but below each stepped action of the shale, to reduce the speed due to gravity acceleration, but without stopping its travel, and drawing off the volatile products from the chamber at suitably spaced intervals.

In testimony whereof I affix my signature.

CLAYTON ORVILLE WHITE.
